UNITED STATES PATENT OFFICE

PETERSON H. CHERRY, OF LOS ANGELES, CALIFORNIA.

TOY.

1,212,903.

Specification of Letters Patent. Patented Jan. 16, 1917.

Application filed March 1, 1916. Serial No. 81,545.

To all whom it may concern:

Be it known that I, PETERSON H. CHERRY, a citizen of the United States, residing at Los Angeles, in the county of Los Angeles and State of California, have invented a new and useful Toy, of which the following is a specification.

My invention relates to toys, and the principal object of the invention is to provide a 10 toy which will furnish amusement, and at the same time serve as a purifying and cleansing agent for the air.

Referring to the drawings, which are for 15 illustrative purposes only, Figure 1 is an elevation partly in section, showing the method of charging the toy. Fig. 2 is a side elevation, showing the method of lighting the toy. Fig. 3 is a side elevation partly in section showing the method of operating the 20 toy, and Fig. 4 is an enlarged section on a plane represented by the line x^4-x^4 of Fig. 3 looking in the direction of the arrows.

In the form of the invention illustrated in the drawings, a standard 11 is rigidly 25 secured in the base 12 which may be of wood or other suitable material. A plunger 11 extends inside a barrel 13 in which it fits

tightly, the barrel 13 gripping the plunger 11 by means of a spring 14 so that the barrel 30 will remain in any position in which it may be placed on the plunger 11. Sliding on the exterior of the barrel 13 is a hub 15 of a bowl 16, the hub 15 being provided with a spring 17 which grips the barrel 13 in the 35 same manner of the spring 14, illustrated in Fig. 4. A projection 171 is formed on the barrel 13 to limit the movement of the hub 15 thereon. The bowl 16 has a lower portion 18 of spherical contour, this spherical 40 portion merging into an upper cylindrical portion 19. A cap 20 fits over the cylindrical portion 19, and a mouth piece 21 is fixed to the top thereof, this mouth piece having an aperture 22 through the center thereof. The 45 mouth piece is flared as shown. For the purpose of conveniently charging the toy, a metal box 23 is provided, this box containing the aromatic material 24, this aromatic material 24 may be resinous gums, or any 50 material which will smolder when ignited. In practice I prefer to make it of tarry substances, which will have the necessary combustible characteristics, and to mix with this tarry material various aromatic and 55 antiseptic materials.

The method of operating the invention is

as follows: The plunger 11 is drawn down to a point near the bottom of the barrel 13, and the barrel is filled by forcing it down into the mixture of aromatic material 24 in 60 the box 23, or the aromatic material may be forced into the barrel with the fingers. The plunger 11 is then forced down to compact the aromatic material in the barrel 13 into a cylinder, the aromatic material being of such 65 a character that it has considerable mechanical strength when compacted in cylindrical form. One method of filling the toy is shown in Fig. 1. The toy is then placed upright on the base 12, and the barrel 13 is 70 forced downwardly until a small amount of the cylinder of aromatic material projects from the upper end of the barrel 13. It may then be lighted as shown in Fig. 2 burning with a small flame. This flame heats the cylinder 75 of aromatic material and compacts it so that after the flame is blown out the aromatic material will continue to smolder, giving off a pleasant odor and serving to disinfect and fumigate the space in which it is 80 placed. The bowl 16 catches and retains any hot particles of the cylinder which may become detached.

If it is desired to operate it as a toy, the barrel 13 is forced up into the position shown 85 in Fig. 3, in which it surrounds the cylinder which is smoldering slowly. The cap 20 is then put in place as shown in Fig. 3, and it is possible to form smoke rings which are shown at 50 in that figure, these smoke rings 90 being formed by pressing the cap 20 quickly down, and expelling a little puff of smoke through the mouth piece 21, this smoke having accumulated between the cap 20 and the bowl 16. The heat of the smoldering material tends to pack the cylinder so that it is 95 welded together and its mechanical strength is greatly increased.

If it is desired to extinguish the aromatic material it may be done either by letting the 100 cap 20 remain at rest, or by pulling the hub 15 up around the cylinder, thus shutting off the air therein.

When the cap 20 is raised a partial vacuum is formed therein, and this causes fresh air 105 to rush in around the smoldering cylinder, thus supplying the oxygen of combustion.

I claim as my invention:—

1. A burner for aromatic material, comprising a barrel in which the aromatic material may be compacted, a bowl surrounding the upper end of said barrel in such a 110

position as to catch any particles of aromatic material that may fall from said barrel, a plunger in said barrel, and a base in which the lower end of said plunger is secured.

5 2. A burner for aromatic material, comprising a barrel in which the aromatic material may be compacted, a bowl surrounding the upper end of said barrel in such a position as to catch any particles of aromatic
10 material that may fall from said barrel, a cap surrounding said bowl and provided with an aperture in the top through which smoke rings may be projected, a plunger in said barrel, and a base in which the lower
15 end of said plunger is secured.

3. A burner for aromatic material, comprising a barrel in which the aromatic material may be compacted, a bowl surrounding the upper end of said barrel in such a position as to catch any particles of aromatic material that may fall from said barrel, a cap surrounding said bowl, a flaring mouth-piece secured in the top of said cap, a plunger in said barrel, and a base in which the lower end of said plunger is secured.

4. A burner for aromatic material, comprising a barrel in which the aromatic material may be compacted, a bowl surrounding the upper end of said barrel in such a position as to catch any particles of aromatic material that may fall from said barrel, friction means for locking said bowl at various positions on said barrel, a plunger in said barrel, and a base in which the lower end of said plunger is secured.

5. A burner for aromatic material, comprising a barrel in which the aromatic material may be compacted, a bowl surrounding the upper end of said barrel in such a position as to catch any particles of aromatic material that may fall from said barrel, friction means for locking said bowl at various positions on said barrel, a cap surrounding said bowl and provided with an aperture in the top through which smoke rings may be projected, a plunger in said barrel, and a base in which the lower end of said plunger is secured.

45

6. A burner for aromatic material, comprising a barrel in which the aromatic material may be compacted, a bowl surrounding the upper end of said barrel in such a position as to catch any particles of aromatic material that may fall from said barrel, friction means for locking said bowl at va-

rious positions on said barrel, a cap surrounding said bowl, a flaring mouthpiece secured in the top of said cap, a plunger in said barrel, and a base in which the lower end of said plunger is secured.

7. A burner for aromatic material, comprising a barrel in which the aromatic material may be compacted, a bowl surrounding the upper end of said barrel in such a position as to catch any particles of aromatic material that may fall from said barrel, a plunger in said barrel, friction means for locking said barrel on said plunger, and a base in which the lower end of said plunger is secured. 65 70

8. A burner for aromatic material, comprising a barrel in which the aromatic material may be compacted, a bowl surrounding the upper end of said barrel in such a position as to catch any particles of aromatic material that may fall from said barrel, a cap surrounding said bowl and provided with an aperture in the top through which smoke rings may be projected, a plunger in said barrel, friction means for locking said barrel on said plunger, and a base in which the lower end of said plunger is secured. 75 80

9. A burner for aromatic material, comprising a barrel in which the aromatic material may be compacted, a bowl surrounding the upper end of said barrel in such a position as to catch any particles of aromatic material that may fall from said barrel, a cap surrounding said bowl, a flaring mouth-piece secured in the top of said cap, a plunger in said barrel, friction means for locking said barrel on said plunger, and a base in which the lower end of said plunger is secured. 85 90

10. A burner for aromatic material, comprising a barrel in which the aromatic material may be compacted, a bowl surrounding the upper end of said barrel in such a position as to catch any particles of aromatic material that may fall from said barrel, friction means for locking said bowl at various positions on said barrel, a plunger in said barrel, friction means for locking said barrel on said plunger, and a base in which the lower end of said plunger is secured. 105 100 105

In testimony whereof, I have hereunto set my hand at Los Angeles, California, this 23rd day of February, 1916.

PETERSON H. CHERRY
